UNITED STATES PATENT OFFICE

140,596

DESIGN FOR A LABELING MACHINE OR SIMILAR ARTICLE

Sidney T. Carter, Worcester, Mass., assignor to
Economic Machinery Company, Worcester,
Mass., a corporation of Massachusetts

Application May 17, 1944, Serial No. 113,624

Term of patent 14 years

(Cl. D55—1)

To all whom it may concern:

Be it known that I, Sidney T. Carter, a citizen of the United States of America, residing at Worcester, in the county of Worcester and Commonwealth of Massachusetts, have invented a new, original, and ornamental Design for a Labeling Machine or Similar Article, of which the following is a specification, reference being had to the accompanying drawings, forming a part thereof,

Fig. 1 is a perspective view showing the front

and left-hand side respectively of a labeling machine embodying my new design;

Fig. 2 is an elevational view of the right-hand side thereof; and

Fig. 3 is a perspective view showing the rear and left-hand sides respectively of a labeling machine embodying my new design.

I claim:

The ornamental design for a labeling machine or similar article, substantially as shown.

SIDNEY T. CARTER.
